METHOD OF WEB RENEWING

Alfred Henry Mackley, Bedford, England

Application March 29, 1937, Serial No. 133,747
In Great Britain March 31, 1936

4 Claims. (Cl. 242—58)

This invention relates to web renewing apparatus. When a web roll of a printing press is nearly exhausted, it is customary to attach the extremity of a fresh web roll to the moving web of the nearly exhausted roll by applying glue to said extremity, rotating said roll with its peripheral speed equal to that of the moving web, and, at the correct moment, bringing the rotating roll into contact with the moving web so that the glued extremity of said roll will adhere to said web and be carried along therewith.

To maintain the extremity of the new roll firmly against the next turn of the roll while said roll is rotating and at the same time permitting it to be paid out immediately it is affixed to the old web, it is customary to use a gummed paper tab which is adapted to fracture when the extremity of the new roll begins to be paid out.

Difficulty has been heretofore experienced in that some of the glue which is applied to the extremity of the new roll may inadvertently get onto the adjacent turn of said new roll with the result that not only the extremity but also the adjacent turn will adhere to the old web.

The invention has for its object the provision of simple means for overcoming this difficulty, and, in accordance with the invention, the paper tab which is employed to maintain the extremity of the new roll against the adjacent turn of said new roll, is provided with an opening in it which, when the tab is in place, exposes a considerable area of the extremity of the new roll but does not expose any part of the said adjacent turn. The glue by which the extremity of the new roll is adapted to be attached to the old web is then applied to said extremity through said opening and said tab serves to shield the said adjacent turn from the glue.

In the accompanying drawing, like characters of reference indicate like parts in the several views and

Figure 1 is a view of a roll of paper or the like, having one end provided with one form of tab suitable for the purposes of this invention;

Figure 2 is a view similar to Fig. 1 but showing a second form of tab;

Figure 3 is an enlarged detailed plan view showing the first form of tab;

Figure 4 is a view similar to Fig. 3 showing the second form of tab; and

Figure 5 is a schematic view showing the manner of connecting material from an almost exhausted roll to the outer end of the material of a fresh roll.

In the embodiments of the invention here

shown, there is disclosed in Figs. 1 and 2, a roll 10 of paper or the like and, in the present instance, the roll is shown as provided with an outer end 11 having converging edges 12, so that the outer convolution of the roll terminates in a point 13. Attached to the end of the roll in Fig. 1 is a specially formed tab 14 and similarly in Fig. 2 there is attached a specially formed tab 15. While these tabs may be of any desired form capable of accomplishing the object of the invention, the tab 14 has been here shown as a circular disc wherein is provided an opening 16. This opening 16 preferably has two sides 17 which converge at the same angle as the sides 12 of the roll. The remaining periphery of the opening is formed by a pair of converging sides 18 connected by an arcuate side 19. Each side 18 forms a blunt angle with the corresponding sides 17 and from this angle in the general direction of the side 17 extends a series of herring bone slits 20, which series terminates at the periphery of the disc forming the tab.

The tab 15 is similarly provided with an opening 21, the lower sides 22 of which converge preferably at the same angle as the edges 12 of the roll. At the outer ends of the sides 12, the opening has its periphery formed by substantially semi-circular edges 23 from the upper ends of which extend converging edges 24 connected by an arcuate edge 25. A pair of weakened lines 30 extend between each edge 23 and the periphery of the tab 15 as at 26, these weakened lines extending in the general direction of the respective sides 22 of the opening. In applying the device, as will be seen from Figs. 1 and 2, the tab is secured to the outer end of the roll 10 in such manner that the extremity of the outer end is exposed through the respective opening 16 or 21. At the same time, no part of the next inner convolution of the roll is exposed through the tab 40 which thus forms a guard around the exposed extremity of the roll. Thus, the tab not only holds the roll end from unrolling, but affords means whereby adhesive may be applied in the opening without such adhesive reaching a part 45 of the roll other than that exposed through said opening.

In Fig. 5, the new roll is indicated at 10a while an almost exhausted roll is shown at 10b. The run of the material from the roll 10b is indicated 50 at 10c and passes around an idler or guide roll 10d in the direction of the arrow A. The new roll or fresh roll 10a has the part exposed through the opening of the tab provided with an adhesive and brought into contact with the ma- 55

terial 10c so that it adheres thereto, as shown by the tab portion 16a in Fig. 5. The roll 10a, in its revolution in the direction of the arrow B, extends away from the material 10c below its tangent point. As it revolves, stress is set up between the lower part 16b of the tab and the upper part so that the tab tears along the weakened lines. By this means, the outer end of the fresh roll is connected to the nearly exhausted roll adjacent its inner end.

10 What I claim and desire to secure by Letters Patent is:

15 1. A method of securing the extremity of a new web to a moving web which is nearly exhausted, which comprises gumming a tab of paper or like material with an opening in it over the extremity of the fresh web so as to fasten it down against the adjacent turn of the roll with the opening exposing a considerable area 20 of the extremity of the web and not exposing the said adjacent turn, applying gum or glue to said extremity through said opening and bringing the glued area into contact with the old web, so that it is carried along thereby, whereupon said tab fractures.

25 2. A method of securing the extremity of a new web to a moving web which is nearly exhausted, which comprises gumming a tab of paper or like material with an opening in it over the extremity of the fresh web with one side of the opening substantially coinciding with the edge of the extremity of the roll so that said extremity is fastened down against the adjacent turn of the roll with the opening exposing a considerable area of the extremity of the web and 30 not exposing the said adjacent turn, applying

gum or glue to said extremity through said opening and bringing the glued area into contact with the old web, so that it is carried along thereby, whereupon said tab fractures.

3. A method of securing the extremity of a new web to a moving web which is nearly exhausted, which comprises gumming a tab of paper or like material with an opening in it, and provided with weakened lines, over the extremity of the fresh web so as to fasten said extremity down against the adjacent turn of the roll with the opening exposing a considerable area of the extremity of the web and not exposing the said adjacent turn, applying gum or glue to said extremity through said opening and bringing the glued area into contact with the old web, so that it is carried along thereby, whereupon said tab fractures along said weakened lines.

4. A method of securing the extremity of a new web to a moving web which is nearly exhausted, which comprises gumming a tab of paper or like material with an opening in it, and provided with weakened lines, over the extremity of said fresh web with one side of the opening and with the weakened lines substantially coinciding with the edge of the extremity of said web so that said extremity is fastened down against the adjacent turn of the roll with the opening exposing a considerable area of said extremity and not exposing the said adjacent turn, applying gum or glue to said extremity through said opening and bringing the glued area into contact with the old web, so that it is carried along thereby whereupon said tab fractures along said weakened lines.

ALFRED HENRY MACKLEY.
